UNITED STATES PATENT OFFICE.

JOHN E. BELL, DECEASED, LATE OF BROOKLYN, NEW YORK, BY LOLA R. BELL, EXECUTRIX, OF BROOKLYN, NEW YORK, AND EDWARD W. ISOM, OF LOCUST VALLEY, NEW YORK, ASSIGNEES TO SINCLAIR REFINING COMPANY, OF NEW YORK, N. Y., A CORPORATION OF MAINE.

APPARATUS FOR CRACKING HYDROCARBONS.

Application filed July 25, 1925. Serial No. 45,976.

This invention relates to improvements in apparatus for cracking heavier hydrocarbon oils, such as gas oil, for the production of lighter hydrocarbon oils, such as gasoline or pressure distillate, by distillation under pressure. This application is in part a continuation of prior applications filed January 17, 1921, Serial No. 437,662, and filed April 8, 1921, Serial No. 459,555 which issued July 10, 28, 1925 as United States Letters Patent No. 1,547,993 and 1,547,994 respectively. The apparatus described and claimed in this application is of special value for carrying out the process of an application filed March 14, 15 1925, Serial No. 15,459.

In cracking hydrocarbon oils by distillation under pressure, the oil is heated to a cracking temperature under pressure and the heavier oil, or a portion thereof, is broken down or "cracked" with the formation of lighter oils which are vaporized and driven off. The cracking operation takes place gradually and progressively, part of the cracked constituents escaping as pressure distillate and part of the heavier cracked constituents remaining and mixing with the charge of oil in the pressure still. A small amount of asphaltic, or pitch-like constituents, or heavy tar is also formed by the cracking operation. This tar remains in the charge and gradually accumulates due to the vaporization of cracked constituents and to the progressive formation of tar constituents. This tar accumulating in the oil 30 in the still tends to deposit on the heating surfaces of the still and in contact therewith tends to form a carbonaceous deposit thereon closely adhering thereto. Such carbonaceous materials and the heavy tar accumulating in the still charge are poor conductors of heat and when deposited on the heating surfaces of the still which are externally exposed to heating gases interfere with heat transfer and insulate the wall from the protection afforded by the oil so that the walls of the still are apt to become overheated, the temperature of the metal of the heat transferring wall increasing over that of the oil to an extent dependent upon the thickness 45 of the deposit and the amount of heat externally delivered to the wall from the heating gases. As a consequence the pressure still must frequently be shut down for clean-

ing or the temperature of the heating gases must be reduced below that which is most 55 efficient. There is also considerable danger involved due to possible bursting of the heat transferring walls at overheated points. The heating surfaces over which heating gases are first circulated are exposed to the 60 highest temperature of the heating gases and absorb the greatest amount of heat, and these surfaces are most apt to suffer. Heating surfaces immediately adjacent the furnace employed to heat the pressure still may 65 also absorb a large amount of heat by direct radiation from the furnace.

According to the present invention, the heating surfaces of the pressure still are protected in a dual manner, both by regulating the character of the oil charge in contact with the heating surfaces and by regulating the temperature of the heating gases. The regulation of the character of the oil charge is carried out to prevent or reduce 70 the accumulation of tar in the oil in contact with the heating surfaces over which the heating gases are first circulated, that is the heating surfaces in contact with the hottest 75 heating gases, and the regulation of the temperature of the heating gases is carried out without decreasing either the capacity 80 or efficiency of either the still or the heating furnace by returning part of the heating 85 gases which have passed over the heating surfaces and admixing them with the fresh heating gases first circulating over the heating surfaces. This dual regulation, in accordance with the present invention, also provides two means of controlling the heating 90 operation, and consequently the cracking 95 operation. This dual regulation also enables an improved operation of the pressure still in the treatment of different charging stocks and for the production of products of varying characteristics.

By returning heating gases at approximately the temperature at which they are discharged from the heating surfaces and admixing them with fresh heating gases from the furnace, the fresh heating gases are tempered without however reducing the efficiency or capacity of the heating operation. The temperature of the heating gases 100 first contacting with the heating surfaces 105 can thus be reduced in an efficient manner

while at the same time the furnace may be operated at high temperatures at which high fuel efficiency is secured. The reduction in temperature of the heating gases so effected 5 reduces the tendency to overheating of the heating surfaces immediately adjacent the furnace with which the heating gases first contact and there is a decrease in the quantity of heat absorbed by these initial heating 10 surfaces with an increase in the quantity of heat absorbed by the remaining heating surfaces. A more uniform distribution of the heating action is thus accomplished while the increased volume of heating gases, due 15 to the recycling of part of the heating gases, results in an increase of velocity which further promotes the rate and efficiency of heat absorption. An increase in both fuel economy and capacity may thus be secured.

20 In addition to this regulation of the temperature of the heating gases, and particularly of the temperature of the heating gases as they first contact with the heating surfaces of the still, fresh oil and reflux are 25 also utilized to protect the initial heating surfaces and to promote the efficiency of the heating operation. The vapors from the cracking operation are subjected to a refluxing operation, and the reflux there- 30 from and fresh oil supplied to the cracking operation are first brought into heat exchange with the heating gases at their highest temperature, that is the fresh oil and reflux are brought into contact with the 35 initial heating surfaces with which the heating gases first contact and before the heating gases are passed over the more remote heating surfaces of the pressure still. As the light cracked constituents are vaporized, 40 and as the oil loses its content of crackable hydrocarbons and as the concentration of tar constituents in the oil increases, the oil is brought into heat exchanging relation with the heating gases which have been 45 tempered both by the return of part of the waste heating gases and by the abstraction of heat on the initial heating surfaces. The reflux is made up of constituents which have been vaporized from the charge of oil in 50 the still and is hence substantially free from tar constituents, and the reflux and fresh oil, which is also substantially tar free, are brought into heat exchange with the heating gases while at highest temperature, and, as 55 tar tends to accumulate in the oil, the oil is passed over heating surfaces in contact with progressively cooler heating gases.

The heating surfaces of the pressure still most apt to suffer are thus protected by 60 absorption of the heat transferred therethrough in heating and cracking the reflux and fresh oil, and the reduced concentration of tar constituents maintained in the oil in contact with these initial heating surfaces 65 prevents or reduces the formation of car-

bonaceous deposits thereon. At the same time, the initial temperature of the heating gases as they first contact with the heating surfaces is also reduced by recycling part of the waste heating gases. The heat available in the heating gases, tempered both by the recycling of part of the waste heating gases and the abstraction of heat through the initial heating surfaces by oil in which a relatively low concentration of tar constituents is maintained, is then further employed to advantage in cracking the oils as tar constituents accumulate therein. 70 75

In the apparatus of the invention, the heating surfaces of the pressure still may 80 be further protected and the heating of the pressure still charge equalized by providing progressively increased areas of heat transfer between the oil and the heating gases as the tar content of the oil increases and as 85 the temperature of the heating gases decreases. The heating effect may thus be equalized by increasing the area of heat transfer as the temperature of the heating gases decreases while an increased area of 90 heating surface is provided in contact with the oil containing an increased tar content where deposition is most likely to occur. The tar content of the pressure still charge 95 may also be controlled and reduced by withdrawing tar from one or more portions of the still charge where the tar tends to accumulate.

The invention will be further described 100 in connection with the accompanying drawings which illustrate in a diagrammatic manner apparatus embodying the invention; but it will be understood that this further description and illustration is for the purpose of explanation and that the invention 105 is not limited thereto.

In the accompanying drawings:

Fig. 1 represents a pressure still, in elevation and section with parts broken away, 110 adapted for carrying out the process of the invention, on line 1—1 of Fig. 2,

Fig. 2 is a section on line 2—2 of Fig. 1,

Fig. 3 represents a modified pressure still, in elevation and section with parts broken away, adapted for carrying out the process 115 of the invention, on line 3—3 of Fig. 4,

Fig. 4 is a section on line 4—4 of Fig. 3, and

Fig. 5 is a section on line 5—5 of Fig. 3.

The pressure still illustrated in Figs. 1 and 2 comprises a drum 6 and a series of tubular heating elements communicating therewith arranged in the heating flue of the furnace 7. The heating flue comprises a series of vertical connecting flues 8, 9, 10 and 11, the flue 8 also connecting with the furnace 7 and the flue 11 with a stack flue 12. The flues are arranged so that the heating gases from the furnace are passed successively therethrough to the stack. The still drum 120 125 130

6 is provided internally with a series of partitions 13, 14 and 15 dividing the drum into a series of compartments, A, B, C and D, and a corresponding series of heating elements 5 separately communicating with each of the these compartments are arranged in the heating flues. The heating element connected to compartment A, is arranged in flue 8, that is the flue through which the 10 heating gases are first passed, the heating element of the next compartment B in the flue 9, and so on, the heating element connected to the last compartment D being arranged in the last heating flue 11 through 15 which the coolest heating gases are circulated. The partitions in the drum do not completely shut off the compartments from each other but extend a short distance above the normal liquid level therein leaving a 20 common vapor space in the upper part of the drum. Overflow pipes 16, 17 and 18 are arranged for progressively transferring oil to successive compartments in the series; and these pipes are provided with bell caps 25 to prevent transfer of surface scum and froth to successive compartments. Arranged above the drum 6 is a reflux tower 19 adapted to receive vapors from the vapor space of the drum 6 and to discharge reflux, 30 and any admixed oil, into the first compartment A. A connection 20 is provided for introducing fresh oil into the upper part of the reflux tower; and a connection 21 is provided for introducing fresh oil directly 35 into the first compartment A. The vapors escape from the reflux tower through vapor line 22 to a condenser diagrammatically illustrated at 23. The pressure in the still may be reduced and controlled by a regulating valve 24 arranged between the reflux 40 tower and the condenser or by a valve 25 arranged beyond the condenser. The reflux tower and the still drum may, with advantage, be covered or protected with suitable 45 heat insulation, such as an asbestos or mineral wool jacket.

To the extent described above, the pressure still illustrated in Figs. 1 and 2 is of construction similar to that illustrated in 50 Figs. 3, 4 and 5 and corresponding parts in Figs. 3, 4 and 5 are designated by the same reference characters with the letter "a" appended. The pressure still illustrated in 55 Figs. 1 and 2 is arranged so that circulation is maintained by convective action, while the pressure still illustrated in Figs. 3, 4 and 5 is arranged so that circulation is maintained by mechanical forcing means such as pumps.

60 Again referring to the pressure still illustrated in Figs. 1 and 2, each of the heating elements connected to the respective compartments comprises three similar groups of heating tubes. Each of these 65 groups comprises an outflow header 26, a series of upwardly inclined tubes 27 arranged through the heating flue for heat exchange with the heating gases therein, connecting headers 28, another series of upwardly inclined tubes arranged through the 70 heating flue, and an inflow header 30. In order to facilitate cleaning and repair the headers are arranged outside of the heating flues and are formed with plugged hand holes in alignment with the heating tubes. 75 In order to equalize the heating effect in the several heating elements and to provide an increased area of heat transfer as the tar content of the oil increases, the heat transferring area of the several headers is progressively increased as the temperature of the heating gases declines. In the still illustrated, the header connected to the first compartment A has four tubes in each group, that connected to compartment B 80 eight tubes, that connected to compartment C twelve tubes, and that connected to the last compartment D sixteen tubes. In order to provide for drainage, and for withdrawal of tar during the cracking operation, the lower ends of the inflow headers in each heating element are connected to a manifold 31 having a valved outlet 32, the outlet from the last compartment D being 85 designated 32'. A draft tube 33 is arranged for withdrawing waste heating gases from a point adjacent the exit of the heating flue 11, the flue in which the heating element connected to the last compartment D is arranged, and returning them to the flue 8 for tempering the heating gases fresh from the furnace 7 in the flue 8. The draft tube may be operated by a steam jet or other suitable forcing means. By-passes 34 and 35 provided with regulating dampers 36 and 37 are provided for further controlling the distribution of heat in the several flues. 90

In the pressure still illustrated in Figs. 3, 4 and 5, the heating elements connected to the respective compartments also comprise three similar groups of heating tubes. Each of these groups comprises a header 38, a series of upwardly inclined tubes 39 arranged through the heating flue, connecting headers 40, another series of upwardly inclined tubes 41 arranged through the heating flue, and a header 42 discharging into the corresponding compartment in the drum 6a. The headers 38 in each group are connected to a common horizontal header 43 which is in turn connected through pipe 44 to the discharge side of a circulating pump. A connection 45 is also provided between each compartment in the drum and the inlet side of the circulating pump discharging through the header connected to that compartment. A separate pump may be employed for each of the compartments, or a series of pumps may be arranged in a common casing and driven by a common driv- 100 105 110 115 120 125 130

ing means as shown in the drawings. The pumps shown in the drawings are of the rotary piston type, sometimes known as Connersville pumps and are particularly adapted for use in carrying out the process of the invention but it will be apparent that pumps of other suitable construction adapted to handle hot oil at the cracking temperature may be employed. The pumps shown are independent and the oil is separately circulated through each of them, partitions being arranged between the several pump chambers to confine the oil in each circulating stream to that stream. A valved outlet 46 is provided in the connection 44' to the last compartment for discharging tar from the pressure still during the cracking operation. A draft tube 47 is arranged for withdrawing waste heating gases from a point adjacent the exit of the heating flue 11^a and returning them to the flue 8^a for tempering the heating gases fresh from the furnace 7^a in the flue 8^a. The draft tube may be operated by a steam jet or other suitable forcing means. By-passes provided with dampers may also be arranged between the heating flues 8^a, 9^a and 10^a as described in connection with the pressure still illustrated in Figs. 1 and 2.

It will be apparent that, in each construction illustrated, the oil supplied to the still is first brought in heat exchanging relation with the heating gases of highest temperature and as the tar concentration of the oil increases the oil is progressively brought in heat exchanging relation with heating gases of lower temperature and that, at the same time, the heating gases are tempered before first being brought in heat exchange with the oil by recirculation of a part of the waste heating gases. The heating surfaces of the pressure still are thus protected in a dual manner, both by regulating the character of oil charge in contact with the heating surfaces and by regulating the temperature of the heating gases. The area of heating surface of the heating elements may also be increased as the temperature of the heating gases declines and as the tar concentration of the oil increases, further protecting the heating surfaces of the pressure still.

In the operation of the apparatus illustrated, the still is initially charged with oil through connection 21, or connection 21^a, the oil successively overflowing into the adjacent compartments as the preceding compartments and heating elements are filled, and the still charge is then brought to the cracking temperature and pressure in the usual way. The pressure employed may differ with different charging stocks and for the production of different pressure distillates. With gas oil character charging stocks for the production of gasoline character distillates, pressures in the neighbor-

hood of 90 to 125 lbs. per sq. in. or more may be employed. In cracking kerosene character charging stock to produce a gasoline character distillate, considerably higher pressures may be used, for example, pressures up to 300 lbs. per sq. in. or more may be employed.

After the still charge is brought to the cracking temperature and pressure, the cracked vapors rise from the several compartments and pass upwardly through the reflux tower 19, or 19^a and the introduction of fresh oil into the reflux tower in direct contact with the vapors therein is begun. In the reflux tower, the fresh oil is intimately contacted with the vapors from the still, refluxing the heavier vapors and preheating the fresh oil, and the reflux and admixed fresh oil are returned to the first compartment A. Additional fresh oil may also be supplied through connection 21, or 21^a. As reflux and fresh oil are supplied to compartment A, oil from this first compartment which has been deprived of part of its crackable constituents and contains some tar constituents overflows into the second compartment B where it is further cracked and a further part of its components are vaporized. In the same way oil is transferred from compartment B to compartment C and from compartment C to compartment D as the cracked constituents are vaporized and as the tar accumulates, the oil in the successive compartments containing less and less of the original oil constituents and more and more heavy tarry constituents. The supply of fresh oil and reflux to the first compartment A also assists in maintaining a low tar concentration in the oil therein. The introduction of fresh oil into the reflux tower may be controlled to regulate the refluxing operation; and where no tar, or only a relatively small amount of tar, is withdrawn the amount of fresh oil introduced into the reflux tower may correspond approximately to the amount of distillate taken off or may be somewhat in excess of this amount. Where larger amounts of tar are withdrawn, the still charge is maintained by the introduction of an increased amount of fresh oil, and the fresh oil supplied may be divided and introduced partly into the reflux tower and partly into compartment A directly, or it may all be introduced directly into compartment A.

The heating gases from the furnace 7, or 7^a, are passed successively over the heating elements connected to compartments A, B, C and D in order so that the oil in the first compartment A, including the reflux and fresh oil supplied to this compartment, is subjected to the highest temperature, that in the second compartment B to a somewhat lower temperature, and so on. However, before the heating gases fresh from the fur-

nace are passed over the heating element connected to compartment A, they are tempered by the admixture therewith of waste heating gases withdrawn from the last heating flue and returned and admixed with the fresh products of combustion leaving the furnace. This tempering of the hottest heating gases assists in protecting the initial heating surfaces in the heating element connected to compartment A and these heating surfaces are further protected by the absorption of heat in the oil circulating thereover which oil contains a high proportion of reflux and fresh oil constituents and a low proportion of tar constituents so that carbon deposition on these heating surfaces is avoided or minimized. The heating gases passing over the heating elements connected to compartment B are thus tempered both by the recirculation of part of the circulating gases and by the absorption of heat in the heating elements connected to compartment A so that as the tar content of the oil increases the temperature of the heating gases declines, while the heating surfaces exposed to the hottest heating gases are protected by the circulation thereover of oil containing the least content of tar. In all of the heating elements the absorption of heat by the circulating oil protects the heating surfaces, and particularly in the first where the heating element is exposed to the hottest heating gases and where the circulating oil contains the reflux and the fresh oil and the least content of tar. As tar accumulates in the oil it is further cracked for the further recovery of the desired pressure distillate but by heat exchange with heating gases progressively declining in temperature as the tar content of the oil increases.

It will thus be seen that the present invention provides an improved apparatus for cracking hydrocarbon oils by distillation under pressure in externally heated pressure stills in which the heating surfaces of the still are protected both by recycling part of the waste heating gases from the still and employing them to temper the fresh products of combustion from the furnace and by supplying fresh oil and reflux to that part of the oil charge circulating over the heating surfaces with which the heating gases first contact, that is the surfaces subjected to the hottest heating gases, so that the oil circulating over these initial heating surfaces contains a low content of tar. The heating gases cooled and tempered in this initial heating operation and by the tempering due to the recirculation of waste heating gases are then employed to further heat and crack the oil as carbon and tar constituents accumulate in it. The oil circulated over the initial heating surfaces thus contains the highest proportion of fresh oil and reflux constituents, and at the same time

these heating surfaces are protected by the recycling of waste heating gases, while as the fresh oil and reflux constituents are cracked and vaporized and as the circulating oil becomes heavier and carbon and tar constituents accumulate therein the oil is circulated over heating surfaces exposed to the cooler heating gases from the preceding heating of oil having a lower tar content. The apparatus of the invention has several important advantages. It enables the cracking operation to be carried out for a longer period without decrease in the rate of cracking. It also enables an improved application of the heating gases to the cracking operation so that both the efficiency and capacity of the pressure still may be increased. Further, it affords improved protection to the heating surfaces of the pressure still particularly to the heating surfaces which are exposed to the most intense heat and to the severest conditions.

We claim:

1. In an oil cracking still, a drum, partitions in the drum dividing the same into communicating compartments, means for feeding the oil into the compartment at one end of said drum, a furnace having a series of heating flues communicating with a fire box, heating units connected to the respective compartments and progressively arranged in the flues, the heating unit connected to the supply compartment being nearest the fire box, and means for returning a portion of the products of combustion from a point in the heating flues more remote from the fire box in the furnace to a point less remote therefrom.

2. In an oil cracking still, a drum, partitions in the drum dividing the same into communicating compartments, means for feeding oil into the compartment at one end of said drum, a furnace having successive communicating flues corresponding to said compartments communicating with a fire box, heating units connected to the respective compartments in the drum and arranged in the respective heating flues, the heating unit connected to the compartment to which oil is supplied being arranged in the heating flue nearest the fire box and means for drawing a portion of the products of combustion from the heating flue most remote from the fire box and returning it to the heating flue nearest the fire box.

3. In an oil cracking still, a furnace having a heating flue communicating at one end with a fire box, a drum adapted to contain a charge of oil, heating means arranged in the heating flue and connections for circulating oil from and to the drum therethrough, a separate heating means communicating with the drum arranged in the heating flue between the first mentioned heating means and the fire box, connections for sup-

plying fresh oil to the still, means for initially circulating the fresh oil through the last mentioned separate heating means, and means for recirculating through the heating flue part of the heating gases which have passed over the heating means of the still.

4. In an oil cracking still, a furnace having a heating flue communicating at one end 10 with a fire box, a drum adapted to contain a charge of oil, a reflux tower communicating with the drum, heating means arranged in the heating flue and connections for circulating oil from and to the drum there- 15 through, a separate heating means communicating with the drum arranged in the heating flue between the first mentioned heating means and the fire box, connections for supplying fresh oil to the still and connections 20 for returning reflux from the reflux tower to the still, means for initially circulating the fresh oil and the reflux through the last mentioned separate heating means, and means for recirculating through the heating flue 25 a part of the heating gases which have passed over the heating means of the still.

5. In an oil cracking still, a furnace having a heating flue communicating at one end 30 with a fire box, a drum adapted to contain a charge of oil, a reflux tower communicating with the drum, heating means arranged in the heating flue and connections for circulating oil from and to the drum there- 35 through, a separate heating means communicating with the drum arranged in the heating flue between the first mentioned heating means and the fire box, connections for returning reflux from the reflux tower to the 40 still, means for initially circulating the reflux through the last mentioned separate heating means, and means for recirculating through the heating flue heating gases which have passed over the heating means of the 45 still.

6. In an oil cracking still a furnace having a heating flue communicating at one end with a fire box, a drum adapted to contain a charge of oil, a reflux tower communicating with the drum, heating means arranged in the heating flue and connections for cir-

culating oil from and to the drum there- 55 through, a separate heating means communicating with the drum arranged in the heating flue between the first mentioned heating means and the fire box, connections for introducing fresh oil into the reflux tower, means for initially circulating the fresh oil and admixed reflux through the last mentioned separate heating means, and means for recirculating through the heating flue a 60 part of the heating gases which have passed over the heating means of the still.

7. In an oil cracking still, a drum having a series of communicating compartments 65 therein, a furnace having a heating flue, heating units in the flue connected to the several compartments, means for supplying oil to be treated to one of said compartments and for causing it to flow successively to the 70 other compartments, mechanical forcing means for maintaining circulation of oil through the heating units connected to the several compartments, the heating unit connected to the supply compartment being 75 nearest to the furnace, and means for returning a portion of the products of combustion from a point in the heating flue more remote from the furnace to a point less remote therefrom.

8. In an oil cracking still, a drum having a series of communicating compartments, 80 therein, a furnace having a heating flue, heating units in the flue connected to the several compartments, means for supplying oil to be treated to one of said compartments and for causing it to flow successively to the other compartments, the heating unit connected to the supply compartment being 85 nearest the furnace, and the heating units connected to successive compartments having progressively increasing heat transferring areas, and means for returning a portion of the products of combustion from a point in the heating flue more remote in the furnace 90 to a point less remote therefrom.

In testimony whereof we affix our signatures.
